DESIGN FOR TEXTILE FABRIC

Bruno Haertel, Providence, R. I., assignor to A. D. Juilliard & Company, Inc., New York, N. Y., a corporation of Delaware

Application April 2, 1935, Serial No. 56,178

Term of patent 14 years

To all whom it may concern:

Be it known that I, Bruno Haertel, a citizen of Germany, residing in the city of Providence, in the State of Rhode Island, have invented a new, original, and ornamental Design for Textile Fabric, of which the following is a specification, reference being had to the accompanying drawing, forming a part thereof, in which:

The fabric embodying the design is a dress and coating material.

I claim:

The ornamental design for textile fabric, as shown and described.

BRUNO HAERTEL.
